COMBINED LAVATORY AND VANITY

August Felcan, Medinah, Ill.

Application January 31, 1958, Serial No. 49,459

Term of patent 14 years

(Cl. D4—2)

Fig. 1 is a front perspective view of a combined lavatory and vanity embodying my new design;

Fig. 2 is a side elevational view thereof;

Fig. 3 is a top plan view thereof; and

Fig. 4 is a fragmentary front elevation illustrating the rear leg structure.

The undisclosed side of the cabinet is the same in appearance as the side that is shown in Figs. 1 and 2.

The dominant features of the design reside in the solid line portions of the drawing.

I claim:

The ornamental design for a combined lavatory and vanity, as shown and described.
